CLAIM

The ornamental design for an inline cable splice housing, as shown and described.

DESCRIPTION

FIG. 1 is a top plan view of an inline cable splice housing showing my new design;

FIG. 2 is a front elevational view thereof, the undisclosed rear elevation being a mirror image of the disclosed front elevation;

FIG. 3 is a bottom plan view;

FIG. 4 is a right side elevational view, the undisclosed left side being a mirror image of the disclosed right side;

FIG. 5 is a top, front and right side perspective view; and,

FIG. 6 is a bottom, rear and left side perspective view.

FIG. 1

FIG. 2

FIG. 4

FIG. 3

FIG. 6
